UNITED STATES PATENT OFFICE.

WALLACE APPLETON BEATTY, OF NEW YORK, N. Y.

MOISTURE-PROOF PACKAGE.

1,369,159.

Specification of Letters Patent.

Patented Feb. 22, 1921.

Application filed June 20, 1919. Serial No. 305,608.

To all whom it may concern:

Be it known that I, WALLACE APPLETON BEATTY, a citizen of the United States, and a resident of New York city, borough of 5 Manhattan, in the county and State of New York, have invented certain new and useful Improvements in Moisture-Proof Packages, of which the following is a specification.

My invention relates to new and useful 10 improvements in moisture-proof packages, and particularly contemplates a package or wrapping which may be used in connection with various products, and particularly those which are susceptible to the absorption 15 of moisture and to loss of flavor when subjected either to moisture or the atmosphere, or both. The invention will be found particularly useful in connection with such delicate substances as hard candies which 20 crystallize rapidly when subjected to moisture, and chewing gums which readily absorb moisture, and in a short time lose their flavor.

As the result of extended work in connection 25 with packages for the purposes stated, I have discovered that it is practically impossible to provide a package which is moisture-proof, and which will prevent escape of flavor when the package consists of 30 organic materials such as paper, whether coated or sealed with moisture-proof materials such as paraffin, or not. I have discovered that the only practical and commercial wrapping for materials of the 35 character above mentioned, which will successfully prevent the absorption of moisture and the loss of flavor, is one consisting of a non-organic substance such as a metallic foil, for example, tin-foil, which is folded 40 or wrapped about the packaged substance so as to completely envelop the same, and sealed at all open or edge and fold portions by means of a suitable cementing material, such for example, a moisture-proof material 45 such as paraffin, preferably.

I have fully and clearly illustrated several 50 embodiments of my invention in the accompanying drawings to be taken as a part of this specification, and wherein—

Figure 1 is a perspective view of a chewing gum package in which the outer wrapping consists of metallic foil sealed at its edge and closure portions by means of a cementing material such as paraffin.

Fig. 2 is a section on the line 2—2 of Fig. 1.

Fig. 3 is a modification of the same invention, showing the tin-foil wrapper covered with an outer layer of wrapper of paper, not necessarily paraffined, in order to protect the foil from abrasion. 60

Fig. 4 is a modification showing the improved package completely enveloped in the cementing material, such as paraffin, instead of being applied only at the edges and 65 folds.

Fig. 5 is a modification in which a plurality of sheets or layers of tin-foil are employed.

Fig. 6 is a further embodiment of the 70 invention as applied to packages or containers of more or less permanent form, the same being shown in vertical central section.

Referring to the drawings by characters 75 of reference, 1 designates a group of chewing gum pieces, each of which may be individually wrapped in paper, either paraffined or not, and a band of retaining paper 2 for maintaining the inner wrapping in 80 position. The group of pieces assembled as shown, is wrapped in a sheet of tin-foil 3 so as to entirely envelop the same. The free edges 4 and folds 5 of the tin-foil are closed and sealed by a cementitious material 6, 85 preferably of a moisture-proof nature, such for example as paraffin, preferably. If desired, the entire package wrapped in tin-foil may be dipped in paraffin or other cementing material instead of merely having its edges and folds sealed, such for example as shown at 7 in Fig. 4. The paraffin may be applied after the wrapping has 90 been placed about the contents, or may be applied to the foil before the latter is 95 wrapped. In the latter case, the folds and ends may be sealed as shown in Figs. 1 and 2, or merely by a hot plate applied to the wrapping to melt the paraffin with which the foil has been previously coated.

If desired, the tin-foil may, as shown in Fig. 2, carry on its inner face a thin sheet of paraffin paper 8, but this may be omitted if desired, its sole purpose being to separate the ordinary commercial tin-foil from the 105 food product wrapped therein. In the form shown in Fig. 2, when employing foil carrying on its inner face waxed or paraffined paper, the wax-like material or paraffin which seals the wrapping is located between the paper carried by the overlying tin-foil and the outer face of the underlying tin- 110

foil which is overlapped by the said paper, as clearly indicated at 6 in Fig. 2. When the paper is omitted, the wax-like material or paraffin which seals the wrapping will be located between the underlying and overlying layers of foil and in direct contact with both of said layers. If the package is wrapped in pure tin-foil instead of the commercial form, the paper may be omitted. If desired, the tin-foil package may have an outer layer of paper 9 (see Fig. 3), either paraffined or not, but this may be omitted, inasmuch as a properly sealed or dipped tin-foil package will efficiently serve its purpose, as far as the exclusion of moisture and the retention of the flavor is concerned without additional external wrapping.

In order to prevent possible admission of moisture and escape of flavor through minute openings in the tin-foil which are not discernible to the naked eye, I may also form the foil wrapping of two layers 10, 10, as shown in Fig. 5, so that any openings which may exist in one layer will be sealed by immediately perforating portions of the other layer. In this form, the layers of foil may be secured together by a film of paraffin or other suitable moisture-proof cementing material, as at 11.

In Fig. 6 of the drawings, I have shown a folded carton package consisting of a container 12 of more or less permanent form, and preferably made of paper or other fibrous sheet material commonly used for the purpose, and cover the same with tin-foil 13 which is sealed hermetically at its folded and meeting edges 14 by means of cementing material, such as paraffin, shown at 15, which foil may, if desired, be additionally wrapped in an external covering of paraffined paper 16, the latter, however, not being essential. In this form of the invention the entire package may be dipped in paraffin or otherwise covered therewith, instead of applying the moisture-proof material to the edges and folds.

No matter which form the invention takes, it is desirable that the meeting and overlapping edges and the fold portions of the foil be efficiently sealed by means of the cementing material, so that no crevices or openings will exist through which moisture may find access to the contents, or through which the flavor of the latter may escape, in other words, the cementing material is located throughout, or is coextensive with, the meeting or overlapped edges of the foil wrapping, and between the laps of the folds. The invention as above described provides the most efficient moisture-proof, and flavor retaining package of which I am aware, and I have demonstrated this by a series of elaborate technical comparative experiments, demonstrating that there is no wrap-

65 per package at present in use, or known, which is comparative at all as to efficiency in a practical sense with my invention. These tests have shown that a package of commercial chewing gum wrapped in accordance with my present invention, and subjected to 70 moisture under a bell jar for two months, shows practically no absorption of moisture whatever, whereas, the ordinary commercial chewing gum wrapped in a paraffined paper package and intended to be moisture-proof, 75 when subjected to the same conditions showed substantial and objectionable absorption of moisture within one week, in fact, to such an extent as to render it useless commercially. The said package above referred 80 to, wrapped in accordance with my invention, at the end of two months in a closed jar, showed, upon opening the jar from time to time, no escape of odor or flavor, whereas, the commercial package wrapped in paraf- 85 fined paper showed the escape of the flavor at all times by mere smelling. Similar tests on hard candies showed the same comparative results, that is, prevention of moisture effects, in the case of hard candies being 90 crystallization of the sugar and loss of flavor.

My invention has the following advantages accruing from the prevention of moisture absorption and loss of flavor: (1) The 95 material so packaged has a longer commercial life, inasmuch, as it will last indefinitely in proper storage, or on store shelves. (2) It results in a vast saving in tin-foil, because individual wrapping of the 100 pieces is not necessary. (3) The manufacturer can employ very much less flavoring material in the manufacture of the food product, because the flavor is retained to practically the same extent as when the 105 goods were first made, which means that the manufacturer does not have to over-flavor his product in order that it will have sufficient flavor when sold after an extended time. (4) The package not only prevents 110 the admission of moisture to the package, but also prevents the escape of the desirable amount of moisture contained in the goods—for example chewing gum—when first manufactured, so that the goods are prevented 115 from drying out to an undesirable degree. This is important in chewing gum manufacture, because in dry climates or under dry conditions, the chewing gum within six months will become stale and brittle, and 120 lose the natural plasticity necessary for a satisfactory chewing gum. In the case of hard candies wherein brilliancy and permanency of color is a commercial necessity, my packaging will prevent the admission of 125 moisture which ordinarily causes crystallization of the sugar and destroys the appearance of the candy, as well as tending to soften the same. I do not limit my invention to its application to confections, as 130

above described, but can apply the same, with equal advantage, to any substance which should be protected from moisture, or loss of moisture, and loss of flavor, for 5 example, coffee, tea, tobacco.

It is to be understood that in the drawings the thickness of the various sheets, coatings and seals have been enlarged for the 10 purpose of clearness, and in order that the invention will be properly illustrated and understood.

What I claim and desire to secure by Letters Patent of the United States is:—

1. A moisture-proof package comprising 15 an inner body of definite form, and an envelop or wrapper of metal foil completely inclosing said body, and having overlapping edges and folds, said edges and folds being hermetically sealed by a wax-like material between said edges and coextensive therewith, and between the laps of said folds.
2. A moisture-proof package comprising 20 an inner carton of substantially rectangular

form, and an envelop or wrapper of metal 25 foil completely inclosing said body, and having overlapping edges and folds, said edges and folds being hermetically sealed by a wax-like material between said edges and co-extensive therewith, and between the laps 30 of said folds.

3. A moisture-proof package comprising an inner carton of substantially rectangular form, and an envelop inclosing the same comprising superposed sheets of paraffined 35 paper and foil completely inclosing said carton, and having overlapping edges and folds, said edges and folds being hermetically sealed by paraffin between said edges and co-extensive therewith, and between the 40 laps of said folds.

In testimony whereof I have hereunto signed my name in the presence of a witness.

WALLACE APPLETON BEATTY.
